AUXILIARY SAILING YACHT

Gary W. Mull, 6677 Gunn Drive,
Oakland, Calif. 94611

Filed Mar. 6, 1968, Ser. No. 10,860

Term of patent 14 years

Int. Cl. D12—06

U.S. Cl. D71—1

FIG. 1

FIG. 1 is a side elevational view of an auxiliary sailing yacht showing my new design;

FIG. 2 is a top plan view of the hull of said auxiliary sailing yacht with mast, sails, and associated elements deleted for ease of illustration;

FIG. 3 is a rear elevational view of the hull of said auxiliary sailing yacht with mast, sails, and associated elements deleted for ease of illustration; and

FIG. 4 is a front elevational view of the hull of said auxiliary sailing yacht with mast, sails, and associated elements deleted for ease of illustration.

I claim:

The ornamental design for an auxiliary sailing yacht, substantially as shown and described.
